UNITED STATES PATENT OFFICE.

BENJAMIN J. GREELY, OF BOSTON, MASSACHUSETTS.

SAFETY-PIN.

SPECIFICATION forming part of Letters Patent No. 393,006, dated November 20, 1888.

Application filed June 4, 1887. Serial No. 240,923. (No model.)

To all whom it may concern:

Be it known that I, BENJAMIN J. GREELY, of Boston, in the county of Suffolk and State of Massachusetts, have invented a new and useful Improvement in Safety-Pins, of which the following is a specification, reference being had to the accompanying drawings, in which—

Figures 1 and 2 are views of my safety-pin patented by my Letters Patent No. 212,216. Figs. 3 and 4 are views of my improved safety-pin; and Fig. 5 shows the blank, plan, and edge view, which serves to hold the wire forming the pin-loop and head-loop in place.

While my patented pin shown in Figs. 1 and 2 is a very excellent safety-pin, it is objectionable in two important respects, viz., it cannot be made so readily and strongly as is desirable, and its pointed end frequently gets unfastened and pricks the wearer.

In the improved safety-pin forming my present invention and shown in Figs. 3 and 4 these objections are overcome, for the safety-pin is very readily and strongly made and likelihood of its pointed end becoming accidentally unfastened is reduced to a minimum.

In Figs. 1 and 2 of the drawings the wire 1, forming the pin-loop of my patented pin, is secured to the plate 2, as shown, and the wire 30 is bent to form the "twisted eye." Pressure upon the leg 3 is exceedingly apt to unfasten the pointed end of that leg from its shield 4, and the way in which the wire is secured to the plate makes the pin look clumsy and unfinished.

In Figs. 3, 4, and 5 blank A of my improved safety-pin is provided with ears a a' a^2 a^3 , and wire B is bent to form the pin-loop b and head-loop b' . The wire thus bent is placed on blank A, and ears a a' a^2 a^3 are bent over the 40 wire to hold it in place, the stub end of the wire being secured and concealed by ear a , which, together with ear a' , forms a shield for the pointed end of the wire. Wire B is bent to form a twisted eye as before, but the legs 45 b^2 b^3 are made substantially parallel to each other for the greater part of their length and pressure upon the pointed leg b^2 does not ordinarily spring the leg out of place.

I am aware of Phelps' patent, No. 232,413, 50 dated September 21, 1880, and disclaim all that is shown in it.

What I claim is—

The improved safety-pin herein described, made up of blank A, having ears a a' a^2 a^3 , and single wire B, pointed at one end and bent to form pin-loop b and head-loop b' , ears a^2 a^3 being bent around the lower bar of head-loop b' and ears a a' bent one around the stub end of wire B and the other around the part of wire 60 B parallel to the stub end of the wire, and the pointed end of the wire being sprung between these bent ears a a' , which form the shield for the pointed end of the wire, substantially as and for the purpose set forth.

BENJAMIN J. GREELY.
